US00D706261S

(12) **United States Design Patent**
Sharma et al.

(10) **Patent No.:** **US D706,261 S**
(45) **Date of Patent:** ** Jun. 3, 2014

(54) **MOBILE COMPUTING DEVICE**

(75) Inventors: **Sameer Sharma**, Santa Clara, CA (US);
Gadi Amit, San Mateo, CA (US);
Yoshikazu Hoshino, San Francisco, CA (US);
Chadwick Harber, San Francisco, CA (US);
Daniel Clifton, San Francisco, CA (US);
Kenneth Jasinski, South San Francisco, CA (US)

(73) Assignee: **Intel Corporation**, Santa Clara, CA (US)

(**) Term: **14 Years**

(21) Appl. No.: **29/411,619**

(22) Filed: **Jan. 24, 2012**

(51) LOC (10) Cl. **14-02**

(57) **CLAIM**

The ornamental design for a mobile computing device, substantially as shown and described.

DESCRIPTION

FIG. 1 is a perspective view of a mobile computing device showing the new design;

FIG. 2 is a front elevation view of the mobile computing device of FIG. 1;

FIG. 3 is a rear elevation view of the mobile computing device of FIG. 1;

FIG. 4 is an elevation view from the right side of the mobile computing device of FIG. 1;

FIG. 5 is an elevation view from the left side of the mobile computing device of FIG. 1;

FIG. 6 is a top plan view of the mobile computing device of FIG. 1; and,

FIG. 7 is a bottom plan view of the mobile computing device of FIG. 1.

The broken lines shown in the drawings represent portions of the mobile computing device which form no part of the claimed design.

1 Claim, 5 Drawing Sheets
